FILTER SHELL

Robert J. Offer, Racine, Wis., assignor to Walker Manufacturing Company, Racine, Wis., a corporation of Delaware

Filed Oct. 24, 1963, Ser. No. 77,136

Term of patent 14 years

(Cl. D46—1)

I claim:

The ornamental design for a filter shell, substantially as shown.
